UNITED STATES PATENT OFFICE.

FREDERICK H. FOSTER, OF RACINE, WISCONSIN, ASSIGNOR TO FOSTER AND WILLIAMS MANUFACTURING COMPANY, OF RACINE, WISCONSIN, A CORPORATION OF WISCONSIN.

PAPER-PAD HOLDER.

No. 918,743.

Specification of Letters Patent.

Patented April 20, 1909.

Application filed October 20, 1908. Serial No. 458,732.

To all whom it may concern:

Be it known that I, FREDERICK HENRY FOSTER, a citizen of the United States, residing at Racine, in the county of Racine and State of Wisconsin, have invented certain new and useful Improvements in Paper-Pad Holders, of which the following is a specification.

My invention relates to certain improvements in holders for pads of paper which may be used for any purpose desired, either memorandum pads, sale slips, letter or bill heads, or in fact packages or pads of paper adapted to be used for any desired purpose.

The object of my invention is to provide a holder of this character which is cheap and simple in construction, composed of few parts and durable.

With these and other objects in view my invention consists in certain constructions, combinations and arrangements of parts the preferred form of which will be first described in connection with the accompanying drawings and then the invention particularly pointed out in the appended claims.

Referring to the drawings wherein for the purpose of illustration I have shown one form of pad holder embodying one of the forms to which my invention is adapted and wherein the same part is designated by the same reference numeral wherever it occurs Figure 1 is a perspective view of the pad holder open; Fig. 2 is a central longitudinal section of Fig. 1; Fig. 3 is a perspective view of the parts separated, showing a construction adapted to connect a sheet to the end of the back and Fig. 4 is a detail perspective view partly broken away with parts separated to more clearly show my construction, and showing a modified form of spring clip.

1 designates the body portion which, as shown, is preferably made of sheet metal and having at one end the up-turned end 2 against which the head of the pad of paper 3 is adapted to rest.

4 designates a groove or depression extending across the body portion 1 a short distance back from the upturned end 2. One edge of the spring clip 5 is adapted to enter this groove so that it will firmly engage the back 1 and the other edge of the clip rests upon the top of the pad as illustrated. This clip is formed of spring metal and may be of cylindrical form, as shown

in Figs. 1 and 2, triangular form as shown in Fig. 3, or of any other shape as may be found desirable, the only essential being that it shall provide two edges, one adapted to engage the groove 4 and the other the pad 60 of paper to clamp the pad firmly in position.

Preferably and as shown the side edges of the back 1 are inturned to form strengthening flanges 6, these flanges preferably extending from the groove to the outer edge 65 of the back.

When it is desired to provide the pad holder with a flexible cover of leather, canvas or similar material, or when it is desired to have a backing sheet of celluloid 70 or the like which is adapted to be placed immediately beneath the first sheet of the pad for the purpose of giving a hard surface upon which to write, or when a carbon sheet is needed I preferably form a holder 75 for such flexible cover or the like by slightly raising the flanges 6, as shown at 7, so that a plate 8 may be slipped in between the flanges and the body of the back, whereby the flexible sheet 9 which may be a cover, a 80 celluloid sheet, or other device will be clamped between the back 1 and the plate 8 and held frictionally in position. In order to avoid any tendency to tear the material so clamped I preferably turn over the outer 85 edge of the plate, as shown at 10.

11 designates the cover which preferably has its longitudinal edges inturned, as shown at 12, in order to strengthen the cover and present smooth sides, and at its inner end 90 has the inturned flange 13 in which is secured a bail 14. The free loop of this bail is so positioned away from the inner end of the cover that the clip 5 can loosely pass therethrough, in order to hinge the cover to 95 the holder, as clearly illustrated in the drawings.

In assembling my device for use a pad of paper is laid upon the back 1 with the top edge of the pad against the upturned end 2 100 of the back. The clip 5 is then slipped through the bail 14 and the edges of the clip forced apart by any suitable tool until the clip can be passed over the back and pad. Upon releasing the clip the pad will 105 be clamped upon the back, and because of the engagement of one edge of the clip with the groove 4 there is no danger of the parts becoming misplaced in use, or where the pad is not too thick it may be depressed against 110

the back and then the clip forced over them. If it is desired to use a flexible sheet 9 as before described, such sheet may be secured to the lower edge of the back by means of 5 the plate 8.

It is to be understood that my holder is adapted for general use and that it can be used with or without the carbon holder as desired.

10 I realize that considerable variation is possible in the details of construction and arrangement of parts without departing from the appended claims, and I therefore do not intend to limit myself to the specific 15 form shown and described.

What I claim as new and desire to secure by Letters Patent is—

1. In a pad holder the combination with the back portion of a cover portion provided 20 with a bail at one end thereof, a spring clip adapted to engage the back portion and a pad of paper to be secured thereto, said clip passing through the bail of the cover to form a hinge.

25 2. In a pad holder the combination with a back having an upturned end, of a cover

provided with a bail at one end thereof, a spring clip adapted to engage the back portion and a pad of paper to be secured thereto, said clip passing through the bail of the 30 cover to form a hinge.

3. In a pad holder the combination with a back portion provided with a groove adjacent one end, a cover provided with a bail extending from one end thereof, a spring 35 clip adapted to secure a pad on the back, said spring clip when in position passing through the bail of the cover and having its engaging edges resting upon the pad and in the groove of the back.

40 4. In a pad holder the combination with a back portion, of means for securing a pad of paper thereon, said back portion having inturned flanges and a plate adapted to be inserted under the flanges at the outer ends 45 for the purpose described.

In testimony whereof I affix my signature in presence of two witnesses.

FREDERICK H. FOSTER.
